UNITED STATES PATENT OFFICE.

HENRY F. BECHMAN, OF BATTLECREEK, MICHIGAN, ASSIGNOR TO DUPLEX PRINTING PRESS COMPANY, OF BATTLECREEK, MICHIGAN.

MULTICOLOR DUPLEX PRINTING.

SPECIFICATION forming part of Letters Patent No. 786,620, dated April 4, 1905.

Application filed June 30, 1904. Serial No. 214,730.

To all whom it may concern:

Be it known that I, HENRY F. BECHMAN, of Battlecreek, in the county of Calhoun and State of Michigan, have invented certain new and useful Improvements in Multicolor Duplex Printing; and I hereby declare that the following is a full, clear, and exact description thereof, reference being had to the accompanying drawings, which form part of this specification.

This invention is an improvement in printing-presses of the well-known duplex flat-bed web-perfected type; and the object of this invention is to enable the duplex press to produce eight pages or less in colors—in other words, to make a multicolor duplex printing-machine. In order to do this, it is necessary to provide a duplex press with an additional printing-couple which may be and preferably is conveniently located parallel with and directly above the usual bed of the duplex press, and the reciprocating cylinder of this third printing-couple may be connected with and operated by the cross-heads of the ordinary duplex press. The web feeding, looping, and delivering mechanism employed in this press are substantially the same as those of the ordinary duplex press, a few additional web-guiding rolls being added for the purpose of drying the web when it is to be printed in colors through the additional printing mechanism.

I do not deem it necessary to illustrate all the parts in detail in the accompanying drawing, as the duplex press is well known, and any one familiar therewith will be able to construct and operate the present invention from the following description in connection with the drawing attached hereto, and I will refer to the claims for summaries of the essential features of the present invention for which protection is desired.

The accompanying drawing represents a longitudinal sectional elevation through a duplex press provided with my improvements and embodying my invention, whereby said press is enabled to perfect eight pages or less in colors.

In said drawing, K K' K² designates feed-

rolls by which the web may be fed into the 50 machine from the web-roll W, it being an eight-page web in a full-sized press. The web then passes under a guide-roll 9, then up over a lower looping-roll 7, down under a guide-roll M', over cross-head guide f, down 55 between lower cylinder H and bed h, up over right-hand cross-head guide f' to and under coaxing-roll m', up over another coaxing-roll m, back over upper cross-head guide f'', down between upper cylinder H' and upper bed h', 60 on over opposite cross-head guide f'', back to guide M, down under upper looping-roll l', then up over guide 2 to the delivery-roll O, which is driven by suitable gearing, indicated in the drawing by the feed-roll. The 65 web is directed by roll O down under a guide 3, said web having been previously slitted by suitable means (as by a cutter on roll O', which coacts with roll O) into two parts w and w'. From the guide O one-half, w', of 70 the web may be passed rearward over deflector 4 and suitable guides to the folder F.

The parts thus far described are practically identical in construction and mode of operation with the ordinary duplex press and are 75 substantially such as are shown and described in the patent to Cox, No. 478,503, July 5, 1892, and the reference-letters used on the drawing correspond to the reference-letters on similar parts shown in said patent. The 80 parts which I shall now describe are those which are added to that press in order to enable it to add colors to the web printed on the lower beds and produce a multicolor sheet. The other half, w, of the eight-page web (in 85 cases where it is only desired to print four of the eight pages in colors) is led up over a guide 5 and then passed forward between the roll O' and roll O², back over a guide 6, down under a guide 7, up over a looping-roll 8, 90 which is mounted in the same looping-frame as the rolls l l'. It then passes down under a guide 7^a and passes (above the cylinder H' and guides M m) to a guide 7^b. It then passes up over a coaxer-roll 7^c, forward, and then 95 back over a cross-head guide f², down under between a third cylinder H² and bed h², up over cross-head guide f², back over a guide

7^a, down under a looping-roll 8^a, (in the same frame as looping-roll 8,) up over a guide 7^c, back to and between the roll O² and O³, by which it is fed out and passes thence over guides 7^f 7^e 7^b to the folder F, where it is superimposed upon the other half, *w'*, of the web and both are folded together.

The cylinder H² and bed h² are practically duplicates of the other beds and cylinders and are arranged, preferably, parallel and in vertical alinement therewith, as shown.

The looping-rolls 8 8^a and the guides 7^a 7^b 7^c 7^d direct the web *w'* between the bed and cylinder h² and H² in substantially the same manner as the main web is fed between the lower beds and cylinders.

It will be observed from the foregoing description that the eight-page web is printed on the lower bed h and is then perfected on the middle bed h' in the instance explained. Where only four pages are to be printed in colors, the web is divided at the roll 3, and a four-page web (or one-half) is carried on direct to the folder F, while the other four-page web (or one-half) is returned over the top bed h², where the perfected web is imprinted in colors, suitable blank spaces having been left on the forms on the lower beds for this purpose.

If it is desired to print more than four pages in colors, the entire web (or eight-page web) may be passed back through the machine in the line of the web *w*. In other words, instead of the web being separated at the guide 3 the entire web is passed back over roll 5 into and through the upper printing mechanism, following the course of the part of the web *w* in the drawing.

The looping-rolls 1 1' 8 8^a are all mounted in the same frame and operated synchronously by the same mechanism which is used to operate the looping-rolls 1 1' in the ordinary duplex press, and practically the delivery mechanism of the old duplex press is utilized to feed in the return length of web *w* through the upper bed and cylinder. An additional cylinder O⁵ may be added to the delivery mechanism, so as to utilize the upper surface of the roll O² as a feed-surface.

The three beds may be used to print an ordinary eight-page paper in black, if it is desired, by dividing the web W either before or after it passes the first bed and cylinder. Half the web would then be passed between the bed h' and cylinder H', and the other half of the web would go directly up to the guide 7^c and be passed then between the bed h² and cylinder H² to be perfected thereby, the two parts of the web being assembled at the folder.

I do not, however, in this application claim this method of printing in black, the object of my present invention being to produce eight pages or less in colors on the duplex press, and this I accomplish by the simple addition to such press of an extra bed and cylinder and

a few extra guiding devices (indicated by the numerals in the drawing) and by the peculiar threading of the web, utilizing the web feeding and looping mechanism of the old duplex press as a means for operating the web in the additional multicolor-printing couple.

I do not restrict myself to placing the color-forms on the upper bed, as obviously they could be placed on one of the other beds, if it is preferred, in which case, of course, the black or perfecting color would have to be run on the top bed.

Having thus described how the full eight-page web may be perfected on the press, it seems unnecessary to explain at length how a smaller number of pages could be perfected in colors on this press, as smaller papers could be perfected in either of the methods above described, and other arrangements might suggest themselves to the pressman.

Having thus described my invention, what I claim as new, and desire to secure by Letters Patent, is —

1. In combination with a press having two stationary beds and coacting reciprocating cylinders, a third printing-couple, means for directing a web through the press, and then directing such web or a part thereof through the third printing-couple, whereby eight or less pages, may be perfected in colors, substantially as described.

2. In combination with a press having two stationary beds and coacting reciprocating cylinders, a third bed and cylinder parallel with and in vertical alinement with the beds of such press, of means for directing the whole or part of the web printed on the lower beds between the upper bed and cylinder, whereby eight pages or less, may be perfected in colors.

3. The herein-described multicolor-printing press, comprising three stationary beds and coacting reciprocating cylinders in alinement, means for feeding a web between two of the beds and cylinders to be perfected thereby, and means for directing the whole or part of said web between the remaining bed and cylinder to receive colored impressions therefrom, substantially as described.

4. The herein-described multicolor-printing press, comprising three parallel stationary beds and reciprocating cylinders in vertical alinement, means for feeding a full-width web between the two lower beds and cylinders to be perfected thereby, and means for directing the whole or part of said web between the upper bed and cylinder to receive colored impressions therefrom, substantially as described.

5. In a printing-press, the combination of three printing-couples, arranged parallel and in vertical alinement, means for feeding a web to and delivering it from two of the couples, means for dividing the web into two parts, means for directing one of these parts to the folder, means for directing the other of said

parts between the third couple to receive a color impression therefrom, and means for directing the multicolored part of the web to the folder and assembling it with the other portion of the web, substantially as and for the purpose described.

6. In a printing-press, the combination of three printing-couples, each comprising a stationary bed and reciprocating cylinder, arranged parallel and in vertical alinement, means for feeding a web to and delivering it from two of the beds and cylinders, means for dividing the web into two parts, means for directing one of these parts to the folder after being perfected, and means for directing the other of said parts after being perfected, between the third bed and cylinder to receive multicolor impressions therefrom, and means for directing the multicolored part of the web to the folder and assembling it with the other portion of the web, substantially as and for the purpose described.

7. The herein-described multicolor-printing press, comprising a plurality of stationary beds and reciprocating cylinders, means for feeding a web between some of the beds and cylinders to be perfected thereby, and means for thereafter directing the whole or part of said web between the other printing mechan-

isms to receive colored impressions therefrom, substantially as described.

8. The herein-described multicolor-printing press, comprising a plurality of printing-couples each comprising a stationary bed and reciprocating cylinder, means for directing a web through one or more of the printing-couples to be printed in one color, and means for thereafter directing the whole or part of the web through other printing-couples to receive another color, substantially as described.

9. The herein-described multicolor-printing press, comprising a plurality of printing-couples each comprising a stationary bed and reciprocating cylinder, and all arranged in alinement, means for directing a web through two of the printing-couples to be perfected in one color, and means for directing the whole or part of the web through the remaining printing-couples to receive another multicolor impression, substantially as and for the purpose described.

In testimony that I claim the foregoing as my own I affix my signature in presence of two witnesses.

HENRY F. BECHMAN.

In presence of—

F. W. DUNNING,
CHARLES G. MECHEM.
